CLAIM

The ornamental design for a animal can cover, as shown and described.

DESCRIPTION

FIG. 1 is a perspective view taken from the top and front of the animal can cover, showing our new design;

FIG. 2 is a top plan view thereof;

FIG. 3 is a front elevation view thereof;

FIG. 4 is a rear elevation view thereof; and,

FIG. 5 is a right side elevation view thereof.

The unshown side is a mirror image of the side shown in FIG. 5.

The bottom and interior of the animal can cover form no part of the claimed design.
